UNITED STATES PATENT OFFICE.

LEO A. WYND AND JULIAN L. SCHUELER, OF PEORIA, ILLINOIS.

GALVANIZING APPARATUS.

Application filed March 20, 1926. Serial No. 96,301.

This invention has reference to the galvanizing of iron or steel articles, such for instance as wire, etc.

The invention has for its principal object 5 a galvanizing apparatus comprising a unit, including a plurality of spaced pans, the individual cross-sectional area of which is substantially less than are pans of standard practice and which, when used for galvanizing wire receive only a small number of 10 wires as compared to such standard pans.

The object of constructing a galvanizing apparatus, including a plurality of small pans, as above pointed out, is, first, any one 15 pan of each unit may be removed and replaced without disturbing any other pan of the unit; second, as each pan accommodates only a few wires, any pan of a unit may be operated without the necessity for operating 20 the other pans of such unit; third, a smaller body of metal is required per wire galvanized; fourth, the use of small pans allows for very much greater heat economy than is possible with standard pans; fifth, the 25 surface of the metal in these small pans may be more easily protected against oxidation than pans of the standard type, and sixth, the cost of such units is very much less than are pans of the standard type.

The invention has for a further object to 30 provide the individual pans of each unit with sectional movable heat and air insulating means.

A further object of the invention is to provide 35 for economically heating each individual pan by preferably electrical means.

A still further object of the invention is to provide a molten metal supply for the individual pans of a unit to replace metal carried out as a coating, or to supply a new pan 40 with molten metal, thus obviating delays incidental to the introduction of metal which is not in a molten state.

The invention has for a still further object 45 to provide in a galvanizing apparatus means for automatically supplying a definite amount of fluxing salts, such as sal ammoniac, at definite intervals or continuously, as the case may be; such feeding means being located at one or both ends of the apparatus, 50 or at any other desirable location.

That the invention may be more fully understood, reference is had to the accompany-

ing drawings, illustrating a preferred embodiment of the invention, in which:— 55

Fig. 1 is a side elevation, on a greatly reduced scale, showing a galvanizing apparatus embodying the invention;

Fig. 2 is a top plan view of Fig. 1, partly broken away; 60

Fig. 3 is a longitudinal sectional view, broken in two and somewhat enlarged, as the same would appear, if taken on the line 3—3, Fig. 2;

Fig. 4 is a cross-section as the same would 65 appear if taken on the line 4—4, Fig. 2;

Fig. 5 is a cross-section as the same would appear if taken on the line 5—5, Fig. 2;

Fig. 6 is a detail in elevation of a wire 70 guide, and as the same would appear on the line 6—6, Fig. 3;

Fig. 7 is a plan of Fig. 6;

Fig. 8 is a detail in elevation of a removable skimmings gate or apron, and as the same would appear on the line 8—8, Fig. 3, 75 and

Fig. 9 is a plan of Fig. 8.

Like characters of reference denote corresponding parts thruout the figures.

In the art of galvanizing, particularly 80 galvanizing of wire and like articles, it is usual and customary, as is well known to those skilled in the art, that the galvanizing pans are constructed of heavy steel plate, three quarters of an inch and more in thickness and up to thirty-two feet in length and up to forty-eight inches wide and up to thirty-six inches in depth. Furthermore, as there can be no riveting or seams below the metal line, these pans are very costly. Then 85 again on account of their great bulk it is extremely difficult to heat these pans uniformly and as one of the results the life of such pan is very short, averaging in the neighborhood of three months. After having been burned out these pans are worthless for further use as molten metal containers. Furthermore, as these pans hold a great many tons of metal there is a considerable delay in replacing pans and the galvanizing 90 unit is out of commission for a considerable length of time. Pans of this character carry as high as sixteen wires, and more, depending on the size of the pan and for whatever number of wires are being galvanized 95 the whole pan must be used and likewise

100

105

when the pan is out of commission no wires at all can be galvanized in that particular unit. In other words, the present type of galvanizing pan is not at all flexible. The 5 large pans, as at present used, offer a very large surface of metal which increases the amount of heat lost by radiation and this large surface also increases the loss of metal due to oxidation. Furthermore, it is very 10 difficult to remove the dross which forms in galvanizing pans and the consequent metal loss from this source.

By the use of the present invention all of 15 these disadvantages are obviated. In the first place, it is not necessary to use heavy steel plate, as ordinary double strength pipe, split in half, or a material of a similar character may be used, and instead of one very 20 large pan a plurality of small pans is used. Then, because these individual pans are small it is a relatively simple matter to heat these pans uniformly and thus prolong the life of the pan materially. Furthermore, on account of the smallness of these pans they 25 may be removed and replaced in an extremely short time, as compared with the ordinary pans. Then, too, it is obvious that when removing one of the small pans a whole galvanizing unit is not put out of commission as all the other pans of the unit function 30 in the normal manner. Another advantage of the smaller pan is the ease with which molten metal may be added from a reservoir, obviating the necessity for heating up cold metal. Furthermore, it is not 35 necessary to operate a whole unit, as any one or more of the smaller pans may be operated without affecting any of the other pans of the unit. In other words the type of construction 40 used is extremely flexible. Furthermore, as only a small surface of metal is exposed this type of construction lends itself to the use of a means for very materially reducing the loss of heat by radiation 45 from the surface of the metal, or the loss by oxidation due to air coming in contact with said metallic surface. Furthermore, the removal of dross is obviously very easy and the small type of pan lends itself well to the 50 use of a zinc proof lining which materially cuts down the formation of dross.

We are aware of the patent to Crich for a wire galvanizing apparatus, No. 301,572, 55 patented July 8, 1884, which so far as our knowledge goes is the closest approach to the inventive thought that we have in mind, but which upon a careful analysis it will be observed is neither similar in construction or in function to the apparatus herein disclosed. The Crich patent shows a furnace with a multiplicity of tubes placed in juxtaposition and all heated from a common chamber. Such an arrangement is both impracticable and uneconomical, two salient 60 features incorporated in the present appa-

ratus. While the Crich patent hints at a method of removing skimmings and dross from these pipes, it is clearly obvious that the dross will not collect at the point indicated and, therefore, it is a practical conclusion to say that the dross could never be removed in the manner provided. 70

Reference being had to the drawings, 1 designates the main body of the furnace which is of suitable length and width, and 75 preferably very shallow in depth. It comprises a brick structure supported at a suitable elevation above the floor line by means of a framework, including base rails 2, standards 3 and cross supports 4. The furnace is formed with a plurality of longitudinally disposed spaced heating chambers 5, which extend approximately from one end of the furnace to the other, and it is to be understood that the courses of brick next adjacent, or forming the walls of these heating chambers, are made of some type of the usual heat insulating materials. As shown, the heating chambers 5 are closed on three 80 sides and open out of the top of the body structure for the placement of heating elements 6, preferably electrical, and, also, for the placement of the pans 7 for holding the molten metal. The pans 7 preferably correspond in length to the length of the furnace proper, and while the heating elements 6 may be placed and removed by first removing the pans, it is obvious, of course, 85 that the same may be removed without removing the pans by providing the end walls 90 of each heating chamber with refractory removable plugs 8, which when removed provide 95 openings for the removing and replacement of the heating elements. 100

The pans 7 may be made from pipe, preferably of the "double strength" type, which after having caps screwed on and welded in place on each end are split in half, thus making two separate pans from each pipe for containing the molten metal. If desirable 105 these pans may be lined with a suitable material such, for example, as fire clay for preventing the molten zinc, which comprises the bath, from coming in contact with the metal of the pan. To support the pans by suspension in the respective heating chambers there 110 is preferably welded to the sides, and longitudinally of the pans, angular supports 9, which rest upon the top face wall of the brick structure forming the furnace and 115 with the body of the pans disposed down in the heating chambers 5, as best seen in Figs. 4 and 5. The angular supports 9 further function as a member to which may be hinged insulating covers 10, of which a plurality are provided for each pan throughout 120 their length, as best seen in Fig. 3.

At each end of the pans a superstructure 125 is provided, which will be described, and the insulating covers preferably occupy the 130

space throughout the length of the pans between these superstructures, and these insulating covers are made as individual units, positioned next adjacent each other, where-
5 by, one may be raised without interfering with any of the others for the purposes of inspection, removal of dross, splicing of broken wire, or other purposes which would suggest themselves to those skilled in the art.

10 The heating elements 6 are shown more or less in a diagrammatic way, according to practice, and it is understood that they may be of any type suitable for the work to be done, and connections are or may be
15 provided for supplying these heating elements with a source of heat from any desirable and suitable source.

Disposed within the pans 7, at or near opposite ends thereof and preferably at given points, and preferably at given distances from each end, are removable aprons 11, see Figs. 8 and 9. These aprons are in height only sufficient to extend down part way into the molten metal within these pans, some-
25 what as shown in Fig. 8, and are preferably formed or provided with a plurality of spaced slots 12 through which the wires move which are to be coated. These aprons function not only as guides for the wires, as seen in Fig. 3, but the skimmings which form are held within the pans between these aprons, disposed at or near the opposite ends thereof. This disposition of the aprons forms in effect compartments 13 at the opposite ends of the pans and between the respective ends thereof and said aprons, and in these compartments are the clean metal surfaces forming the ingress and egress ends for the wires which are being coated, al-
30 lowing such wires to enter and leave the coating bath through a clean zinc system. The metal in the compartments 13 of the pans is kept unoxidized and free of foreign matter by the introduction of sal ammoniac, or some other suitable flux which is fed thereto at intervals or continuously as may be desired. Such sal ammoniac or flux is deposited in hoppers or bins 14 supported by superstructures 15 located at each end of
35 the furnace and above the compartments 13 of the respective pans, as best seen in Figs. 3, 4 and 5. Such hoppers or bins are pro-
40 vided with depending chutes 16, one for each pan, and extending downwardly to a point immediately above the tops of the pans and in the lower ends of each chute are journaled for rotation feeding members 17, which may or may not have the form of fluted rollers, and said members are carried
45 on shafts 18, one for each series of members, and on one end of each of said shafts is a sprocket wheel 19 connected by a sprocket chain 20, adapted to receive its power from any suitable source, whereby, they may be
50 operated intermittently or continuously as

occasion may require. The chutes 16 above the feeding members are partitioned and pro-
55 vided with feeding openings 21, adapted to be covered by adjustable sliding valves 22, which are manually regulated so as to pro-
60 vide more or less feeding of the sal ammoniac or other flux from the hoppers to the feeding members, the latter discharging the same onto the coating metal in the compartments 13.

70 In Figs. 1, 2 and 3 of the drawings we have illustrated a furnace which includes a unit of three pans in width with three wires being conducted through each pan, but it is to be understood that the furnace may be
75 of any desired width, and a unit of pans may comprise one or more as may be de-
sired. The wires are designated A and are preferably conducted to the pans and to the compartments 13 therein in a substan-
80 tially vertical direction, and on entering a compartment 13 pass under grooved guiding rollers 23, thence extending through the pans and through the slots 12 in the aprons 11, and then directed from a compartment
85 13 at the exit ends of the pans in a sub-
stantially vertical direction, after first pass-
ing around similarly grooved guiding rollers 23, all of which is best seen in Fig. 3.

90 The apparatus as described, using sal am-
moniac or other suitable flux to provide
95 clean zinc surfaces at the ingress and egress
ends of the pans and directing the coated
wires in a substantially vertical direction
therefrom, provides an apparatus for galva-
nizing wire which obviates the necessity of
100 using the usual or ordinary wiping means
or a heat-treating furnace which is now
known, and makes possible the coating of
105 wire with a heavy, flexible and malleable
bright surfaced coating, even when using
"Prime western zinc" as a coating medium.
Conducting the wires from the pans in a
110 substantially vertical direction with such
an apparatus allows for a smooth uniform
coating to be formed around the wire with-
out recourse to smoothing mediums, such as
wipers, or the heat-treating furnace herein-
before mentioned.

115 The apparatus embodies in its scope the use of the same for the purposes above out-
lined, and if desired the apparatus may be used for ordinary galvanizing purposes by the omission of the aprons 11, mechanism
120 for supplying sal ammoniac or other flux and by the use of well known wiping means, or in place of the wiping means some suit-
able skimming mechanism and heat-treating
furnace for heat-treating the coated wires as they leave the pans.

125 It should now be apparent that by con-
structing a furnace of the type herein dis-
closed, by providing a unit of a plurality
of pans with individual heating units for
130 each pan, that one or more pans may be

4
employed as desired, and only those pans which are in use heated. It being noted that pans may be put into operation in the numbers desired, or discontinued, without affecting any of the other pans of the unit, also, that with the hinged insulated covers for the pans that access may be had thereto as occasion may require, as, for instance, for splicing wires, removing dross, etc. Furthermore, the use of such hinged insulated covers for the respective pans prevents constant contact of air with the top of the molten metal bath and thus keeps the amount of oxide skimmings to a minimum. The furnace is preferably provided with a receptacle 24, removably seated within a chamber 25, provided with a heating unit 26 of substantially the same character as the heating units 6 and adapted to receive its heat from the same source of supply. The purpose of this receptacle is to act as a reservoir for molten metal which may be ladled therefrom into the respective pans 7 at any time it is necessary to add additional

metal, thereby, obviating the necessity for adding cold metal to the pans 7 and causing them to be chilled off.

This application is a companion to the application filed by applicants on February 26, 1926, for a process of coating materials having an iron or steel base, Serial No. 90,868.

What we claim is:—

In a galvanizing apparatus, in combination, a furnace provided with a plurality of longitudinally disposed and spaced heating chambers, a pan for each chamber removably supported therein, individual heating means for each pan, means for dividing the said pans into compartments at each end, and means located above each end of the furnace adapted to supply a flux to the end compartments of said pans to provide a clean zinc system for the ingress and egress of articles through said pans.

JULIAN L. SCHUELER.
